L. P. FEDOWICZ

HYDRAULIC HOIST FOR AUTOMOBILES

Filed Jan. 20, 1922

Fig. 1.

INVENTOR

Louis P Fedowicz

UNITED STATES PATENT OFFICE.

LOUIS P. FEDOWICZ, OF BROOKLYN, NEW YORK.

HYDRAULIC HOIST FOR AUTOMOBILES.

Application filed January 20, 1922. Serial No. 530,653.

To all whom it may concern:

Be it known that I, LOUIS P. FEDOWICZ, a citizen of the United States, residing at Brooklyn, in the county of Kings and State of New York, have invented certain new and useful Improvements in a Hydraulic Hoist for Automobiles, of which the following is a specification.

This invention relates to motor vehicles and more particularly to the turning means therefor.

This invention has for its object the provision of means whereby a motor vehicle may be turned in a short space so as to dispense with the necessity of running the vehicle forwardly and backwardly a number of times when it is desired to turn around.

A further object is to provide a turning device for motor vehicles which is simple to operate, durable in use, and cheap to manufacture.

Other objects and advantages of the invention will be apparent during the course of the following description.

In the accompanying drawing forming a part of this application and in which like numerals are employed to designate like parts throughout the same,

Figure 1 is a side elevation of the invention applied, parts being broken away.

Figure 2 is a group perspective of a power transmitting member embodied in the invention.

Figure 3 is a detail sectional view through the invention.

In the drawing wherein for the purpose of illustration is shown a preferred embodiment of the invention, the numeral 6 designates a motor. As illustrated in Figure 1, the motor 6 is provided with a drive shaft 7 to which a clutch 8 is connected.

The invention forming the subject matter of this application resides in novel means whereby the forward portion of the vehicle may be elevated and moved in an arcuate path and the invention consists of a cylinder 8' adapted to receive fluid pressure from a pipe 9 having control means preferably located adjacent the driver's seat of the vehicle so that when desired fluid pressure may be introduced into the cylinder.

When the fluid under pressure is introduced into the cylinder 8' the piston 12 in the cylinder is moved downwardly for imparting a corresponding movement to the

upwardly extending branch 14 of a horizontally disposed axle 15. A turning wheel 18 is provided with a hub 19 which is rotatably mounted on the axle 15 and having a pinion 20 which meshes with the pinion 22 on the lower end of a shaft 23.

The shaft 23 is slidably extended into a sleeve 26 and is connected thereto by means of a radially arranged lug 28 which as illustrated in Figure 3, is slidable in a longitudinal slot or groove 30 in the inner wall of the sleeve. By reason of this construction the rotation of the sleeve 26 will rotate the shaft 23 so that the wheel 18 will also be rotated for moving the vehicle in the proper direction.

The upper end of the sleeve 26 is formed with a gear 33 adapted to be engaged by a pinion 34 having a hub section 36 feathered on the shaft of the engine. When the gear 34 is in mesh with the gear 33 the sleeve 26 is of course rotated for imparting a rotary movement to a wheel 18. However, the pinion 34 is rotated only when the improved turning device is in operation and the gear 34 may be moved to its inoperative position by means of a fork 39 having connection with a crank arm 40. The crank arm 40 is connected with an adjusting rod 42 having a handle 43 arranged adjacent the operator's seat. With reference to Figure 1, it will be seen that the adjusting rod 42 is movable through the dash 46 of the vehicle and is provided with locking means for engagement with a holding member 48 mounted on the dash.

In operation, when it is desired to turn the vehicle, fluid under pressure is introduced into the cylinder for depressing the piston and thereby elevating the forward portion of the vehicle. When the forward portion of the vehicle has thus been elevated, the gear 34 is moved into mesh with the pinion 33 and the operation of the engine rotates the wheel 18 so that the vehicle is turned to the desired extent. When the vehicle has been turned the gear 34 is released from engagement with the pinion 33 and the fluid under-pressure is allowed to escape from the cylinder 8' so as to allow the front wheels 41 of the vehicle to again contact with the ground.

In carrying out the invention the sleeve 26 is rotatably extended through a sheath 49 rigidly connected to the cylinder 8' by a connecting bar 50. The upper portion of the

sheath is provided with anti-friction elements 53 which contact with the under side of the gear 53 whereby to reduce friction between the gear 33 and the sheath to a minimum. The sheath 49 forms a reliable means for supporting the sleeve 26 and for holding the shaft 23 in position.

The lower portion of the shaft 23 may be rotatably extended into the axle 15 and the axle may be provided with a longitudinally curved bracket 60 having an attaching means 62 to encircle the shaft 23.

I claim:—

The combination with a vehicle having an engine provided with a drive shaft, of a cylinder carried by the vehicle adapted to receive fluid under pressure, a horizontal axle having one end extending upwardly and provided with a piston within said cylinder, a ground contact wheel carried by the

other end of said axle, a vertical shaft carried by said horizontal axle for turning movement with relation thereto, beveled gears connecting said horizontal axle and said vertical shaft, a housing about the upper end of said vertical shaft, a gear carried by said housing feathered to said vertical shaft adapted to permit said shaft to slide with relation thereto, a gear upon said drive shaft and feathered thereto, and means for bringing said second gear in mesh with said gear carried by said housing for driving the ground wheel.

In testimony whereof, I have affixed my signature in the presence of two witnesses.

LOUIS P. FEDOWICZ.
